UNITED STATES PATENT OFFICE.

HARRY M. NACEY AND MICHAEL F. AHEARN, OF CHICAGO, ILLINOIS.

DRY-PIPE VALVE.

Application filed April 28, 1921. Serial No. 465,080.

To all whom it may concern:

Be it known that we, HARRY M. NACEY and MICHAEL F. AHEARN, citizens of the United States, and residents of Chicago, in the county of Cook and State of Illinois, have invented certain new and useful Improvements in Dry-Pipe Valves, of which the following is a specification.

This invention relates to improvements in dry pipe valves enclosed in a housing connecting an underground water main or branch with an automatic sprinkling system, the piping for which is filled with air when exposed to a freezing temperature because of insufficient heating facilities therefore, and particularly when located in cold storage vaults, open driveways, loading platforms, etc., the pressure of which air and a number of devices maintains the valve in its operative seated position against the pressure of the water in the main, and in which heretofore mechanical devices, pure and simple, have heretofore been solely relied upon for tripping the valve following the discharge of air from the sprinkling system from the unseating of any one of a number of sprinkling heads, due to the melting of their fusible link.

The object of our invention broadly stated, is to successfully utilize a column of mercury expediting the seating of a dry pipe valve of any construction, and eliminating the possibility of delay in its unseating from rust, deposits of sediment or other foreign matter in the joints of the locking and unlocking devices therefor, which is otherwise liable to occur, and particularly when, as heretofore, mechanical devices are exclusively employed for controlling the unseating of the valve.

More specifically stated, the object of our invention is to provide a means by which a column of mercury may be practically and successfully utilized for discharging water from the water main into the valve housing in advance of and following the unseating of the valve and until the level of the water therein operates to disconnect the valve from the devices locking it against its seat.

A further object of our invention is to provide a dry pipe valve and disconnectible locking devices therefor, and adapted, on the unseating of the valve, to be instantly moved out of the path of the currents of

water passing directly from the water main through the valve housing into the piping of a dry pipe system, and whereby there is from the beginning a free and unobstructed flow of the water from the main into and through the pipes for such a system.

With these ends in view, our invention finds embodiment in certain features of novelty in the construction, combination and arrangement of parts by which the said objects are attained, all as hereinafter fully described with reference to the accompanying drawings and more particularly pointed out in the claims.

In said drawings,

Fig. 1 illustrates, in vertical section, a dry pipe valve structure in which our invention and inventions find their embodiment.

Fig. 2 is a plan view of the same, with the upper portion of the valve housing removed; and

Fig. 3 is a detail section taken on the line 3—3 of Fig. 2.

The housing 4 for the valve is provided at one side with a hand-hole cover 5 secured and tightened in its closed position by a number of nut-bolts 6, 6, passing therethrough and through flange 7 of the housing, and, as usual, the upper end opening 85 thereof is connected with the dry pipe 8 of an automatic sprinkler system by means of a number of nut-bolts 9, passing through flanges 10 and 11, respectively projecting from the dry pipe and the housing, the boss 12 at the bottom end of the housing being secured, as usual, to a water main or branch 13 by nut-bolts 14 passing through the respective flanges 15 and 16 of the boss 12 and the water main or branch 13.

The inner end of the boss 12 is provided with a seat for the valve, next below which, and extending through the boss, is an alarm opening 18, closed when the valve is seated by means of a lug 17^a projecting downwardly from the valve into a grooved seat 18^a formed in the boss 12.

The inwardly projecting end of the boss 12 has an outward projection 20, provided with recesses receiving lugs 21, 21, through which is passed a pivot rod 22 for hinging the valve at one side to the boss, on which projection 20 are spaced parallel lugs 22, 22, receiving an arm 23, passing through which and through the lugs is a pin 24.

110

Opposing lever 23 is another lever 25, pivotally secured to the housing by means of lugs 26, 26 and a pin 27, each of the levers 23 and 25 being provided with a lug 28, 28, impinging upon the valve 17 next to their respective hinges.

The length of these levers is such that their free ends terminate at a point slightly removed from the axis of the seated valve, as shown in the drawings, and both levers are more or less resilient for the purposes hereinafter described.

Located on the upper side of the valve are lugs 29, 29, between which is pivoted one end of a latch plate 30 by means of a pin 31, which latch plate projects transversely across the opposing ends of the levers 23 and 25 in the path of a trigger 32, pivotally confined between lugs 33, 33, by a pin 34 on the end of a rod 36, supporting at its free end a float 36, operating to disconnect the trigger from the latch when forced upwardly by rising water supplied to the housing from any source whatever.

In this connection it is now to be noted that the purpose in having the fulcrumed levers more or less resilient is to provide a means for depressing the ends of the levers from their normally operatively inclined position by means of the latch toward and before it becomes engaged with the trigger for thereby imparting to the levers a force swinging the levers away from and towards an upright position before the valve is unseated, and a force also sufficient to prevent possible rust and deposits of foreign matter in the bearings of the levers in the latch from retarding their swinging movement, the unseating of the valve and its swinging movement.

In practice, the several locking devices are of sufficient strength to successfully resist the unseating of the valve from any water pressure opposed to the seated valve until, from some source, water supplied to the valve housing lifts the float to its position for operatively disconnecting the latch from its trigger.

Among the advantages attributable to the novel construction and arrangement of the valve locking devices are the few parts required; the simplicity of their construction; the cheapness of their cost; the lack of liability to get out of order; their adaptability to be unlocked when connected with a float positively operated by rising water supplied to the valve housing from any source; the rapidity of the movement of the several devices therefor; and of the valve out of the path of the currents of water passing directly through the valve housing and with which the valve is swung out of the same path by the force of the water from a water main, regardless of any construction or means employed in connection

therewith for controlling the unlocking and unseating of the valve.

Our invention, however, further includes a simple and effective means certain in operation for controlling the unlocking of the valve in advance of its being forced off its seat by the force of water directed against its under surface, and dispense with the use of a weighted lever pivoted to the valve and the use of gearing or spring-actuated devices heretofore used for controlling the unseating of the valve.

In short, our invention contemplates and provides for the use of a column of mercury and to which end we provide the casing at one side with a pocket or receptacle therefor, as indicated at 37 in Fig. 1, in open communication, adjacent its bottom, with a nipple 38, projecting therefrom in a horizontal plane, provided with a coupling 39, connecting it with a vertical tube 40, screw-threaded in and in open communication with a chamber 41, the walls 42 for which may be formed integral with or cast separate and secured to the outer wall of the valve housing.

Opening into and secured to the upper end of the chamber 41 is a nipple 43, which, by means of couplings 44, 44 and a shorter nipple 45, is connected with a downwardly projecting pipe 46, in turn connected by a coupling 47 with a horizontal pipe 48 screw-threaded in a passage 49, opening into the water main or branch pipe 13 below the pocket 37 and therefore substantially below the seated valve 17, as a means for introducing water from the water main into the housing for actuating the float 36 and unlocking the valve before the direct pressure of the water against the valve unseats it, which supply of water is controlled by a needle valve 50 projecting in and seating against the opposing end of a passage 51 secured to a float 52, guided in its movement by means of a pin or rod 53, projecting into the pipe 40.

The float 52 is operated to seat the needle valve 50 by means of a column of mercury 54 so that no air can escape from the housing when the valve is seated and before the float rises sufficiently to unlock the valve.

When, however, the pressure of air in the housing against the column of mercury exposed thereto is below that required for maintaining the needle valve 50 against its seat, then the mercury in the chamber 54 will descend by gravity therefrom and in the tube 40 until it has reached a level common to the pocket and the pipe 40, followed in the meantime with water under whatever pressure it may be in the main, the degree of which pressure is found in practice to be sufficient to force its way through the mercury and into the valve housing, and cause the float to gradually but quite quickly

rise to a level, disengaging the latch 35 from the trigger 32 for and unlocking the valve from its seat, as before described, in connection with the locking devices therefor, 5 and whereupon the valve will be instantly lifted by the water pressure of the main to contact with the under surface thereof and quickly forced to an upright position out of the currents of water ascending through the 10 housing into the piping for an automatic sprinkling system.

The water main or branch pipe 13 is, as usual, provided with a gate (not shown) located substantially below the housing for 15 the dry pipe valve and which is closed immediately following the completion of the active operation of the sprinkling system, the water from which is discharged through the opening 18, and may be through a drain 20 valve in the pipe 46 which is not shown but the location of which is indicated in Fig. 1.

Following the discharge of the water from the housing to a plane below the dry pipe valve seat, the cover 5 is taken off, followed by moving the valve to its seated position and connecting the locking devices therefor in their operative position and whereupon the cover 5 is again secured in its 30 seated position, and whereupon and following the restoration or substitution of fusible link valves in their operation in the piping of the system, air is again introduced therein at a pressure sufficient for the mercury to 35 lift the float 52 and force its needle valve 50 to a seated position.

So far as we are aware, our invention is the first to provide for the successful use of a float in a dry pipe valve housing actuated 40 by rising water therein from any source, and particularly which provides a means by which a column of mercury may be and is adapted, through the operation of a float, for controlling the unseating of a valve 45 when directly opposed to the water pressure in a main or branch therefrom.

In conclusion, it is now to be observed that, so far as we are aware, our invention is the first to provide locking devices of any 50 construction by which their disconnection is practical and possible in advance of the valve being unseated by the pressure of water opposed thereto, or in which the locking levers are propelled away from contact 55 with the valve out of the path of the currents of water forcibly ascending through the valve housing into the piping of an automatic sprinkling system.

Having described our invention, what we 60 claim and desire to secure by Letters Patent is:

1. A device of the class described, comprising in combination a dry pipe valve seating against an opposing pressure of water, a disconnectible locking device for

securing the valve upon its seat, a float operating to unlock the valve, a normally closed by-pass connecting the water under pressure below the valve with a compressed air chamber above the valve, and means controlled by the reduction of the pressure of air in the air chamber for opening the by-pass. 70

2. A device of the class described, comprising in combination a water pipe, a compressed air chamber associated therewith, a valve closing the pipe from the air chamber, a lock for the valve, a by-pass from the water pipe to the air chamber, a float in the by-pass above the water pipe valve, and a 75 heavy liquid in the by-pass cooperating with the float. 80

3. A device of the class described, comprising in combination a valve, a disconnectible locking device maintaining said valve 85 on its seat against an opposing pressure of water, and means including a column of mercury adapted for controlling the disconnection of said locking device in advance of the unseating of the valve. 90

4. A device of the class described, comprising in combination a valve, disconnectible locking devices for maintaining said valve on its seat against an opposing water pressure, a float associated with the locking 95 devices, and a column of mercury operating to automatically furnish a supply of water above the valve to lift the float and thereby disconnect said locking devices. 100

5. A device of the class described, comprising in combination with a valve, of a device for locking said valve on its seat against an opposing pressure of water, consisting of levers each of which is pivoted at one end to the valve seat outwardly from the valve, a latch hinged to the valve which in its locked position projects across the surface of said levers, a trigger pivotally mounted upon the valve, and a float integrally connected with said trigger and 105 adapted to disconnect the trigger from the latch by means of water supplied to and 110 locked in the valve housing when the valve is locked in its seated position.

6. A device of the class described, a valve 115 interposed between the valve housing and a water supply pipe thereto, a by-pass connecting the water supply pipe with the valve housing, a mercury receptacle in said housing projecting below the valve, a tube for 120 said mercury projecting outwardly from and extending upwardly at the side of the housing, a needle valve interposed between the water inlet of the by-pass and the mercury therein, and a float seated and unseated 125 by the rise and fall of the mercury in said pipe and in turn by the rise and fall of air pressure in the valve housing.

7. A device of the class described, comprising a valve, levers fulcrumed on the 130

valve for locking it on its seat, a pivoted latch adapted to depress the free ends of the levers against the resistance of their fulcrums, a float and a trigger secured to said float adapted for engagement with the latch following the depression of the opposing free ends of the levers.

In witness whereof, we have hereunto set our hands this 26th day of April, 1921.

HARRY M. NACEY.

MICHAEL F. AHEARN.

In the presence of witnesses:—

E. J. WALSH,

M. P. HUFFMAN.
